UNITED STATES PATENT OFFICE

2,107,594

POLE BRACKET AND INSULATOR

Frank Bicknese, Worthington, Minn.

Application March 3, 1936, Serial No. 66,937

1 Claim. (Cl. 173—314)

This invention is a bracket or clamp adapted to be applied to a telegraph pole for supporting telegraph wires or other wires of high conductivity and the object of the invention is to provide a bracket or clamp of this character which when used on telegraph poles will serve to so support the conductor as in the event the same becomes heavy due to the accumulation of ice, sleet and the like thereon, the conductor wire by reason of the added weight will readily free itself of the clamp or bracket and drop to the ground for the entire length of the conductor, thereby preventing looping of the wire at intervals as now generally occurs because of the weight added thereto by the accumulation above mentioned.

The invention together with its objects and advantages will be best understood from a study of the following description taken in connection with the accompanying drawing wherein:

Figure 1 is a perspective view illustrating the application of the invention.

Figure 2 is a longitudinal sectional view through one form of my improved clamp or bracket, and

Figure 3 is a view similar to Figure 2 illustrating a slightly modified form of clamp or bracket.

Figure 4 is a detail elevational view illustrating the application of the invention to the curved cross arm of a telegraph pole.

Referring to the drawing by reference numerals it will be seen that in both forms thereof the improved clamp or bracket indicated generally by the reference numeral 5 comprises a pair of complementary slightly longitudinally curved or bowed clamping jaws 6, 7 respectively preferably formed of spring metal or other suitable material.

The jaw 6 is formed from a relatively elongated strip of the desired material bent and shaped to provide a body plate 4 from one end of which extends the jaw 6 and from the other end 40 of which projects an upstanding attaching flange 8 through the medium of which and suitable fastening means 9 the bracket is secured to the telegraph pole or post 10.

The other jaw 7 is formed from a shorter length 45 of the desired material which latter is bent so as to provide a body plate from one end of which the jaw 7 extends in operative position to the jaw 6. The plate 11 rests on the plate 4 and is secured to the latter through the medium of a suitable fastening element or elements 12.

Thus it will be seen that when suitably applied to the post 10 the jaws 6 and 7 of the bracket will be spaced laterally therefrom to accommodate therebetween the conductor wire 13.

At the free end thereof the jaws 7 are provided

with heads 14 of insulating material. These heads 14 are applied to the jaws in any suitable manner preferably by having end portions of the jaws embedded within the material of the head as suggested for example in the form of the invention shown in Figures 1 and 2, although it will be understood, and as shown in Figure 3 the free ends of the jaws 6' and 7' may be applied to the outer faces of the heads designated in said figure by the reference numeral 14a and secured to said heads by rivets or the like 15.

In the form of the invention shown in Figures 1 and 2 the heads 14 have upper beveled ends 16 which when the jaws are in closed position form therebetween a groove for receiving wire 13 as 15 clearly shown in Figure 2. Also, the heads 14 taper longitudinally toward their free ends and have beveled confronting faces 17 which form therebetween a guide channel which facilitates the introduction of the wire 13 between the heads 20 of the jaws for engaging the wire or cable 13 with the clamp, as is thought to be apparent. In the form of the invention shown in Figure 3 the heads 14a at their free ends have beveled confronting faces 17a to facilitate the introduction of the wire 25 or conductor 13 therebetween, and at their inner ends the head 14a are blunt or squared as shown. Adjacent said inner ends the heads 14a have the meeting or confronting faces thereof complementary grooved as at 18 to positively receive 30 therebetween the wire 13 as clearly shown.

It will be apparent that with either construction, and in the event the wire 13 becomes excessively heavy due to the accumulation of ice, sleet or the like thereon the weight of the wire will 35 tend to cause the latter to move downwardly between the heads of the jaws, the jaws readily spreading apart to permit the wire or conductor 13 to pass downwardly therebetween and drop to the ground.

From the above it will be seen that I have provided an efficient clamp or bracket for supporting telegraph wires or analogous conductors from poles in such a manner as will preclude the breaking or snapping of the wires when placed under 45 stress due to accumulations of snow, sleet or the like thereon.

In Figure 4 is illustrated the application of the clamp or bracket to the curved cross arm of a telegraph pole, and in applying either type of 50 clamp it will be apparent that all that will be necessary is to twist the clamp slightly where the parts 4 and 11 of the complementary members of the clamp are riveted together, and as will be believed to be clear to those skilled in the art. 55

Having thus described the invention, what is claimed as new is:

Means for suspending and insulating a conductor from a telegraph pole consisting of a pair of strap members having angularly extending upper ends secured to each other and provided at said upper ends with means for attaching the strap members in suspended spaced parallel relation to

a pole, said strap members having free curved ends forming complementary jaws, heads of insulating material on the free ends of said jaws, said heads having inner beveled ends providing a substantially V-shaped groove therebetween to receive a conductor or line wire. 5

FRANK BICKNESE.
